DESIGN FOR A GLASS SUGAR BOWL OR SIMILAR ARTICLE

Walter von Nessen, New York, N. Y.

Application July 29, 1936, Serial No. 64,119

Term of patent 14 years

To all whom it may concern:

Be it known that I, Walter von Nessen, a citizen of the United States of America, residing at New York, in the county of New York and State of New York, have invented a new, original, and ornamental Design for a Glass Sugar Bowl or Similar Article, of which the following is the specification, reference being had to the accompanying drawing, forming a part thereof.

The characteristic feature of the design resides in the ornamentation shown in full lines.

I claim:

The ornamental design for a glass sugar bowl or similar article substantially as shown and described.

WALTER VON NESSEN.
